UNITED STATES PATENT OFFICE.

GEORGE H. FORSYTHE, OF CHICAGO, ILLINOIS.

DISK WHEEL.

Original application filed November 26, 1918, Serial No. 364,353. Divided and this application filed February 21, 1921. Serial No. 446,661.

To all whom it may concern:

Be it known that I, GEORGE H. FORSYTHE, a citizen of the United States, residing at Chicago, in the county of Cook and State 5 of Illinois, have invented certain new and useful Improvements in Disk Wheels, of which the following is a specification.

This application is a division of my pending application Serial No. 264,253.

10 The invention of this application relates to metal wheels and more particularly of that type characterized by the employment of a disk body portion associated with a fixed rim or felly portion adapted to receive 15 a demountable rim and has for its primary object a strengthening of the disk body against deformation by radial or lateral shocks incident to use. This object is attained by the provision of a rear support 20 of the disk adjacent the hub portion where such strains are greatest.

It has been proposed to strengthen the disk body of this type of wheel by employing a tapered disk of greatest thickness at 25 its center and gradually decreasing in thickness towards its periphery; also by the employment of radial ribs of greatest thickness adjacent the hub; also by radial flutings or corrugations. These expedients not only 30 detract from the appearance of the wheel but also entail greater cost of production and usually a greater weight. By the use of the present invention I am enabled to use in the construction of the wheel body, metal 35 of light gauge uniform throughout its extent, and to produce a wheel of smooth surface front and rear and possessing high powers of resistance to deformation in use.

In order that the invention may be readily 40 understood by those skilled in the art, I have set forth in the accompanying drawing and in the following detailed description predicated thereon different wheel structures embodying the invention.

45 In these drawings—

Fig. 1 is a vertical section through a single disk wheel wherein the invention is embodied;

Fig. 2 is a similar view of a double disk 50 wheel having the disks in contact one with the other and a support for both at the point of contact; and

Fig. 3 is a similar view of a wheel of the

double disk type, having the disks spaced apart adjacent the hub, and a support for 55 the rearmost disk.

With particular reference to Fig. 1 of the drawing, corresponding to Fig. 3 of the parent application, the wheel hub is indicated by the reference numeral 11 and is provided 60 with the front hub plate 12 and with the rear hub plate 13, the latter extending for some distance radially beyond the front plate 12 and developed into the ordinary 65 brake drum 14. Intermediate the two hub plates, in the space ordinarily occupied by the spokes of a wooden wheel, is disposed a filler member 15. The body of the wheel comprises the forwardly concave disk 16 70 having its inner portion clamped between the filler member 15 and the hub plate 12 by means of the bolts 17 and with its outer peripheral portion beaded over at 18 to form a footstep bearing support for the 75 rim-retaining shim 19, the disk being then 80 reversely bent to form a tire-carrying or felly portion 20 upon which the demountable rim 21 is received directly or through the 85 mediation of a supplemental felly member 22; the shim 19 being fulcrumed for rocking 90 movement upon the bead 18 under the influence of the tightening bolts 23.

It will be observed that the radial extension of the hub plate 13, forming the rear wall of the drum 14, lies immediately to the 95 rear of and against that portion of the disk indicated at 24 and the outer margin of the hub plate 13 underlies the shouldered portion 25 of the disk, thus efficiently supporting that portion of the disk body adjacent 100 the hub where it is subjected to the greatest deforming stresses in use.

In Fig. 2, corresponding to Fig. 13 of the parent application, is shown a wheel embodying a front disk 24 and a rear disk 25 105 the inner portions of which are disposed on opposite sides of the filler member 15 and clamped thereon by the bolt 17. The front disk 24 is forwardly concave, and the rear disk in its central portion is substantially plane, the two disks lying in contact with each other throughout the area of greatest concavity of the front disk 24. The hub plate 13, rigidly associated with the hub proper lies against the rear plate 16 110 throughout the area of contact between the

two plates, thus forming an efficient rear support for the wheel body at the place where it is subjected most to deforming stresses.

5. In Fig. 3, corresponding to Fig. 8 of the parent application, is illustrated a modified form of double disk wheel wherein the front disk 26 and the rear disk 27 are spaced apart in their central portion and clamped, as in 10 Fig. 2, between the hub plates 12 and 13 and the filler member 15. In this form of construction the rear disk 27 bears rearwardly against the hub flange 13 at 28 and is shouldered at 29 to overlie the outer margin 15 of the plate 13 for radial support thereon.

I claim:

1. In a disk wheel, the combination with a forwardly concave disk body portion, of a rigid rear support for the disk adjacent the hub.
2. In a disk wheel, the combination with a forwardly concave disk body portion, of a rigid rear support for the disk, said support forming a part of the hub.
3. In a disk wheel, the combination with a forwardly concave disk body portion, of a rigid rear support for the deepest portion thereof, said support fixedly associated with the hub.

4. In a disk wheel, the combination with the disk body portion, of a rigid rear support therefor, said support consisting of a plate fixedly secured to the hub.

5. In a disk wheel, the combination with the forwardly concave disk body portion, of means fixedly associated with the hub at the rear of the disk for supporting the disk radially.

6. In a disk wheel, the combination with a disk body portion having a rearwardly extending shoulder at a distance from the hub, of a plate fixedly secured to the hub at the rear of the disk and underlying the shoulder to provide a radial rear support therefor.

7. In a disk wheel, the combination with a disk body portion forwardly concave and provided with a bend or shoulder, of a plate fixedly secured to the hub and bearing against the shoulder to form a support therefor.

8. In a disk wheel, the combination with a disk body portion forwardly concave and provided with a bend or shoulder, of a plate fixedly secured to the hub and underlying

the shoulder to provide a radial support therefor.

9. A steel disk wheel comprising a hub portion, a medial disk portion, and a felly portion, the forward face of the disk concave and provided with a forward bend or shoulder between its center and the periphery.

10. A steel disk wheel comprising a hub portion, a medial disk portion, and a felly portion, the disk forwardly concave, the material of the disk extending forwardly adjacent the periphery of the hub plate to bear thereagainst.

11. A steel disk wheel comprising a hub portion, a medial disk portion, and a felly portion, the material of the disk extending forwardly adjacent the periphery of the hub plate to bear thereon and again inwardly adjacent the hub proper to form a bearing thereon.

12. A steel disk wheel comprising a hub portion, a medial disk portion, and a felly portion, the disk forwardly concave, the material of the disk extending forwardly adjacent the periphery of the front hub plate to bear thereon and again inwardly adjacent the hub proper to form a bearing thereon.

13. The combination with a hub, of a disk having an ogee curvature between its central and peripheral portions, and a supporting member arranged upon said hub and contacting with a portion of such ogee curvature.

14. The combination with a hub having a barrel and hub, of a disk having a flat central portion, a dished outer portion and an axially turned intermediate portion, and a supporting member arranged upon said hub, and contacting with said hub and said central and turned portions of said disk, and means for connecting said parts together.

15. The combination with a hub, of a brake drum arranged thereon, said drum having an annular supporting shoulder, and a disk having an annular shoulder, fitted upon said annular shoulder of the brake drum, and means for connecting said parts.

In testimony whereof I have hereunto subscribed my name in the presence of two subscribing witnesses.

GEORGE H. FORSYTH.
